UNITED STATES PATENT OFFICE.

FREDERICK L. H. SIMS, OF TORONTO, ONTARIO, CANADA, ASSIGNOR TO THE DIAPHONE SIGNAL COMPANY, LIMITED, OF TORONTO, CANADA.

METAL BENDING AND FORMING MACHINE.

1,336,660.

Specification of Letters Patent. Patented Apr. 13, 1920.

Application filed November 30, 1917. Serial No. 204,692.

To all whom it may concern:

Be it known that I, FREDERICK L. H. SIMS, of the city of Toronto, in the county of York, Province of Ontario, Canada, a subject of the King of Great Britain, have invented certain new and useful Improvements in Metal Bending and Forming Machines, of which the following is a specification.

10 This invention relates to machines for making split slotted bolts such as shown in my co-pending application No. 78,465 filed February 15th, 1916. This bolt is formed from a half-round blank bent on itself and 15 having a slot formed therein by bending and displacing the metal of the blank, and my object is to devise a machine which will take a blank, bend it, form the slot, and discharge the bolt finished save for heading.

20 I attain my object by means of the constructions hereinafter more specifically described and illustrated in the accompanying drawings in which—

Figure 1 is a plan view, partly in section, 25 of my bolt-forming machine;

Fig. 2 a side elevation of the same, partly in section;

Fig. 3 an end elevation of the same; and

30 Fig. 4 a vertical section taken just in front of the forming rolls, parts also being shown in section.

Fig. 5 is a perspective view of the machine partly broken away.

Fig. 6 is a perspective detail on a larger 35 scale illustrating the operation of bending.

In the drawings like numerals of reference indicate corresponding parts in the different figures.

The main elements of my apparatus are 40 the forming rolls 1, the drum 2 carrying the core members or tongues 3 to coöperate with the forming rolls, the bending anvils or supports 4, and the stripper 5 for withdrawing formed bolts from the core members 3.

The rolls 1 are secured to parallel shafts 45 6 suitably journaled on the frame 7 longitudinally of the apparatus. These shafts are geared together by means of the intermeshing gear wheels 8. One of these gear wheels meshes with the pinion 9 on the shaft 10 journaled on the frame 7, and provided with the gear wheel 11 meshing with the pinion 12 on the driving shaft 13. The gearing,

it will be noted multiplies the power of the 55 driving shaft 13 at the expense of speed.

The drum 2 is formed in halves secured together by bolts 14, and on each side is formed a bevel gear wheel 15. With these bevel gear wheels mesh the bevel pinions 16 60 secured to the inner ends of the shafts 6 of the forming rolls, so that the movements of the forming rolls and drum 2 exactly synchronize. The drum itself is secured to the shaft 17, journaled transversely on the 65 frame 7 in substantially the same plane as the axes of the forming rolls 1.

The core members 3 are detachably secured to the drum. Preferably they are fitted into recesses formed between the 70 halves of the drum and secured in said recesses by means of the wedges 18, which, owing to the open construction of the drum, are easily reached from the inner end by suitable tools, so that they may be driven 75 up tightly to hold the core members in place. If any portion of a core member becomes unduly worn, it may be shifted in or out or reversed with very little trouble. As the wedges are driven from the inner 80 side of the rim of the drum, any outward pull on the core members or tongues which takes place during the operation of the machine tends to tighten rather than loosen the wedges, so that in operation the core 85 members will not loosen.

Each tongue in cross section is of substantially the exact dimensions of the slot to be formed in the bolt, and the forming rolls are so shaped as to coöperate with these 90 tongues or core members to shape the bolt around them and thus produce the offsetting of the material of the blank both depthwise and transversely of the slot, which produces a bolt with a slotted end having substantially the same cross sectional area of metal therein as the non-slotted portion of the stem without material increase of the periphery of the slotted as compared with the non-slotted portion of the bolt as described in the application hereinbefore referred to and as illustrated in Figs. 5 and 6 of the drawings of this application. Preferably the movable dies are employed so that they may easily be replaced if they 105 become worn, or different sizes employed.

As will appear on reference particularly to Figs. 2 and 4, the dies 19 are formed

with dovetailed bases fitted into dovetailed slots extending transversely of the rims of the rolls. The dies are held in place by suitable keys or pins 20 driven through the 5 roll and the base of the die transversely to the shaft of the roll. Each die has a half-round circumferential groove formed therein, the central portion of which is offset toward the center of the roll a distance substantially equal to half the thickness of the 10 slot formed in the bolt. Just behind each die the surface of each roll is sufficiently cut away so that while the opposed surfaces of the two rolls will press the halves of the 15 blank above the slot toward one another, they will not interfere with the movements of a formed bolt in the direction of the axis of the roll, which movement must take place during the stripping operation herein- 20 after described.

While the blanks may be bent by being pressed between the rolls by the action of the core members 3 as shown in Fig. 6, yet I prefer to perform as much of the bending 25 operation as possible before the blank is engaged by the rolls. I therefore provide the bending supports 4, hereinbefore referred to, which are supported just above the forming rolls as shown and which are separated by a space preferably somewhat wider 30 than is necessary for the passage of the blank if its halves were bent into close contact. The upper surfaces of the supports are provided with half-round grooves, 35 which grooves preferably incline downwardly toward the center of the supports, the corners where the grooves meet the inner faces of the supports being rounded as shown to facilitate the bending down of the 40 blank. The groove is preferably tilted slightly as indicated particularly in Fig. 2 toward the rear; so that the flat surface of the blank will be struck squarely by the core member which engages it. The inclination of the upper surface of the supports 45 is very important as it brings the points of support of the blank at the time bending commences so far from the center that the preliminary bending takes place under comparatively small pressure and no great pressure is exerted until the blank has assumed 50 a flat V-shape when heavy pressure can no longer effect any longitudinal displacement of the blank as it is likely to do if the blank is originally supported close to the center.

The operation of the apparatus I have so far described will be readily apparent. The blank being in position on the supports 60 4 and the machine being set in operation, one of the core members will strike the blank, the center of which has been held so that it will readily bend, and the blank is forced down between the supports, bending it so that by the continued movement of

the tongue it is readily forced down with its bent end between two of the dies 19. These dies have a movement toward one another due to the circular path in which they travel and coöperate with the tongue or core member to give the slotted end of the bolt the 70 desired shape.

The parts of the blank forming the non-slotted portion of the stem of the bolt are pressed together by the portions of the rolls 75 immediately behind the dies.

The formed bolt is withdrawn from between the dies by the continued movement of the core member, the dies separating as they pass below the plane of the axes of the 80 rolls, and thus permitting the withdrawal of the formed bolt. The formed bolt being securely held on the tongue, means must be provided to withdraw it. This is the function of the stripper 5 hereinbefore referred to. The stripper is suitably secured to the frame and is slotted for the passage of the core member 3, see particularly Figs. 2 and 4, and is provided at each side of the slot with a curved shoulder 21, which curved shoulders in the direction of their length recede gradually from the center of the drum 2. The finished bolt is thus stripped from the core member as indicated in dotted lines in Fig. 2. 95

To carry away the finished bolts I provide the endless conveyer 22, of any ordinary type, driven by the shaft 23 suitably journaled on the frame, provided with a toothed wheel 24 with which a pin 25 on the gear wheel 11 is adapted to mesh, as shown particularly in Fig. 3. As the gear wheel 11 rotates once for each two rotations of the forming rolls, and as two dies are secured to each forming roll a small movement is imparted to the conveyer each time a bolt is dropped from the stripper. 100

In practice an automatic feeding device will be employed to feed blanks on to the bending supports 4, but such feeder forms 110 no part of the present invention.

Preferably a stop 26 is provided against which one end of a blank placed on the supports may be caused to abut so that each blank is accurately centered on the 115 supports.

The core members I have found are liable to become overheated owing to the length of time they are in contact with the heated blanks. I therefore provide a tank 27 below the drum 2, which contains a cooling liquid into which the core members dip as the drum rotates. 120

What I claim as my invention is:

1. In a machine for forming bent slot- 125 ted bolts, the combination of a pair of coöperating rolls journaled on parallel axes and each provided with a plurality of equally spaced dies at its periphery, each die having a circumferential half round groove formed 130

in its face, a portion of each groove being offset toward the center of the roll to permit the metal of the bolt blank to be offset laterally according to the thickness of the slot to be formed in the bolt, the surface of each roll being sufficiently cut away behind each die to permit of the withdrawal of a formed bolt from between the rolls in a direction parallel to the axes of the rolls, when the 10 said cut away parts of the rolls are in juxtaposition.

2. In a machine for forming bent slotted bolts, the combination of a pair of forming rolls suitably journaled to rotate in synchronism and carrying coöperating dies adapted to substantially contact with each other, each die having a circumferential half round groove formed in its face, a portion of each groove being offset toward the 15 center of the roll to permit the metal of the bolt blank to be offset laterally according to the thickness of the slot to be formed in the bolt; and a substantially flat sided tongue carried by a rotatable shaft so as to be movable to and from a coöperating position relative to the dies, the tongue and dies being proportioned to bend a blank around the tongue and to offset the metal of the blank 20 into the offset portions of the half round 30 grooves.

3. In a machine for forming bent slotted bolts, the combination of a pair of forming rolls suitably journaled to rotate in synchronism and carrying coöperating dies adapted 35 to substantially contact with each other, each die having a circumferential half round groove formed in its face, a portion of each groove being offset toward the center of the roll to permit the metal of the bolt blank to be offset laterally according to the thickness of the slot to be formed in the bolt; a substantially flat sided tongue carried by a rotatable shaft so as to be movable to and from a coöperating position relative to the dies, the tongue and dies being proportioned to bend a blank around the tongue and to offset the metal of the blank 40 45 into the offset portions of the half round grooves; and a stripper having a bolt engaging surface inclined in a plane parallel to the axes of the rollers and adapted to draw off formed bolts endwise of said tongue as the tongue moves by the stripper.

into the offset portions of the half round grooves; and a stripper having a bolt engaging surface inclined in a plane parallel to the axes of the rollers and adapted to draw off formed bolts endwise of said tongue as the tongue moves by the stripper.

4. In a machine for bending and forming metal blanks, the combination of a pair of forming rolls suitably journaled for coöperation; a drum journaled to rotate in a plane between the axes of the rolls and provided with tongues adapted to pass between the rolls; and a water tank located so that the aforesaid tongues may pass through water contained therein as the drum is rotated.

5. In a machine for forming bent slotted bolts, the combination of a pair of coöperating rolls journaled on parallel axes and each provided with a plurality of equally spaced dies at its periphery, each die having a circumferential half round groove formed in its face, a portion of each groove being offset toward the center of the roll to permit the metal of the bolt blank to be offset laterally according to the thickness of the slot to be formed in the bolt, the surface of each roll being sufficiently cut away behind each die to permit of the withdrawal of a formed bolt from between the rolls in a direction parallel to the axes of the rolls, when the said cut away parts of the rolls are in juxtaposition; and a substantially flat sided tongue carried by a rotatable shaft so as to be movable to and from a coöperating position relative to the dies, the tongue and dies being proportioned to bend a blank around the tongue and to offset the metal of the blank into the offset portions of the half round grooves; and a stripper having a bolt engaging surface inclined in a plane parallel to the axes of the rollers and adapted to draw off formed bolts endwise of said tongue as the tongue moves by the stripper.

Signed at Toronto, Canada, this 17th day of November, 1917.

FREDERICK L. H. SIMS.
